B. P. COBB

STOCK GUARD FOR RAILROADS

Filed Jan. 5, 1924

Fig. 2 Inventor,
Benjamin P. Cobb
Louis Bagge & Co
By his Atty's

UNITED STATES PATENT OFFICE.

BENJAMIN P. COBB, OF BOZEMAN, MONTANA.

STOCK GUARD FOR RAILROADS.

Application filed January 5, 1924. Serial No. 684,619.

To all whom it may concern:

Be it known that I, BENJAMIN P. COBB, a citizen of the United States, residing at Bozeman, in the county of Gallatin and

5 State of Montana, have invented certain new and useful Improvements in Stock Guards for Railroads, of which the following is a specification.

This invention relates to stock guards 10 for railroads, and is especially adapted for use at intersecting fields to prevent the stock passing along the railroad from one field to the adjoining field.

The object of the invention is to provide 15 such a device which is simple in construction and of such a nature as to not impair the life of the stock.

In the drawings:

Fig. 1 is a top plan view; and 20 Fig. 2 is a transverse section on the line 2—2 of Figure 1.

The letters A and B indicate the rails of the usual railroad secured to the ties C. This guard preferably consists of a plurality 25 of more or less flexible metal bands 1, 2 and 3 placed centrally of the track and along either side thereof, being of sufficient width to practically close the space between the tracks and a given width on 30 either side. Each band is provided with a loop 4 and 5 at either end thereof, each loop receiving a fulcrum pin 6 and 7, the ends of said fulcrum pins being received in securing members 8 and 9 secured to the ties 35 C. The bands are of such a length that when the looped ends are arranged in place, the band assumes an arched position as shown in Figure 2 being of sufficient height to extend upwardly to approximately the 40 level of the top of the rails.

As stated, these bands are preferably constructed of somewhat flexible material although of sufficient strength to resist possible injury. Secured to the under side of each band is an audible signal or warning 45 in the form of a bell 10, which when the band is disturbed will warn and scare the animal approaching. Each band is preferably painted of stripes of very brilliant color in order that it may be readily observed. 50

It will thus be seen that I have constructed a simple and effective guard made of comparatively few parts, and one that is very durable and efficient in operation. 55

I claim:

1. A stock guard comprising a plurality of arched bands mounted between and adjacent each side of the rails, said bands extending longitudinally of the rails having 60 their ends pivotally supported upon the ties.

2. A stock guard comprising a plurality of arched bands mounted between and adjacent each side of the rails, said bands extending longitudinally of the rails, each 65 band provided with a loop at the end thereof pivotally supported upon the ties.

3. A stock guard comprising a plurality of arched bands mounted between and adjacent each side of the rails, said bands extending longitudinally of the rails, each band provided with a loop at the end thereof pivotally supported upon the ties, and an audible signal carried by each of the bands. 70

In testimony whereof I affix my signature.

BENJAMIN P. COBB.
